WEEDING TOOL

Michael J. Kushner, Robert Kushner, and
John Ponganis, Dearborn, Mich.

Application February 4, 1957, Serial No. 44,729

Term of patent 14 years

(Cl. D35—2)

Fig. 1 is a top plan view of a weeding tool, showing our new design with the handle omitted for ease of illustration;

Fig. 2 is a side elevational view thereof with a portion of the handle broken away to indicate indeterminate lengths.

The dominant features of our design reside in the full line position of the drawings.

We claim:

The ornamental design for a weeding tool, as shown and described.
